UNITED STATES PATENT OFFICE.

MIGUEL DE MARIA ARRIJOA, OF NEW YORK, N. Y. **BEST AVAILABLE COPY**
NON-REFILLABLE RECEPTACLE. **BEST AVAILABLE COPY**

1,255,572.

Specification of Letters Patent. Patented Feb. 5, 1918.

Application filed March 17, 1916. Serial No. 84,758.

To all whom it may concern:

Be it known that I, MIGUEL DE MARIA ARRIJOA, a citizen of the Republic of Mexico, and resident of the city of New York, in 5 the county of New York and State of New York, have invented a certain new and useful Non-Refillable Receptacle, of which the following is a specification.

This invention relates to non-refillable receptacles for liquids. Such receptacles are utilized by manufacturers to prevent their refilling with spurious goods for palming off the substitutes upon the public.

The principal object of my invention is 15 to provide a simple, inexpensive, and efficiently operative receptacle, wherefrom the contents may be readily extracted and which cannot be thereafter refilled.

Other objects and advantages will herein- 20 after appear.

In the accompanying drawings,—

Figure 1 shows a general perspective view 25 of the receptacle.

Fig. 2 is a view similar to Fig. 1 but showing the receptacle with its hinged door removed therefrom.

Fig. 3 shows a perspective view of the hinged door of the receptacle.

Fig. 4 is a cross-sectional plan view of the 30 receptacle.

Fig. 5 shows a sectional elevation of the valve which forms part of the invention.

Fig. 6 is a perspective view of a detail of the invention.

35 The receptacle proper, made of any suitable material, is of a general triangular configuration in horizontal cross-section, Fig. 4, and comprises top and bottom walls 1, an upright, straight, rectangular wall 2, and

40 an arched wall 3, which adjoins the wall 2 at its edge 4 and is concentric with the opposite edge 5 of said straight wall. The remaining or closing wall of the receptacle consists of a door 6 which is hinged as shown

45 at the edge 5 of wall 2 and may be swung about its hinge in the direction of the arrow, Fig. 4, from an outwardly position shown to an intermediate position within the receptacle as indicated at 7 and to an

50 innermost position as indicated at 8, until it is disposed right up against the inner side of the wall 2. When the door 6 is thus swung inwardly its outer edge 9, provided with a rubber packing 10, Figs. 3, 6, in a

55 groove 11 thereof, bears tightly against the

interior side of arched wall 3, and return movement or return swinging of the door, while it is in any position, is prevented by means of metal inserts 12 projecting from a wire 13 secured to the packing-strip 10 bearing against the arched wall 3. Any attempt at swinging the door 6 backwardly to open the receptacle would cause the inserts 12 to bind against the wall 3 and prevent return swinging of the door. 65

In order to fill the receptacle, it is positioned as shown in Fig. 4 and its door 6 is fully opened, whereupon the liquid contents may be inserted therein and the door 6 then closed. When it is desired to extract liquid 70 from the receptacle the operator presses with the fingers of one hand against the exterior side of the wall 2 and against the exterior side of the door 6. The door is thereby swung inwardly and is caused to compress 75 the liquid contents, which is in turn forced to press against a valve 14 secured to the upper part of wall 2. The liquid is compelled to bear against a diaphragm 15 of said valve and moves it away contrary to the pressure of an operating spring 16 thereof, and then the liquid passes through a bent passageway 17 and outwardly from the orifice or outlet 18 of said valve.

It will be evident that any attempt to refill the receptacle by forcing liquid through the orifice 18 would be frustrated by the valve-diaphragm 15 which obstructs the passageway 17, and due to the bent form of said passageway it would prevent reaching 90 therethrough to the valve-diaphragm 15 with any implement in an attempt to move it back contrary to the pressure of its spring 16.

Variations may be resorted to within the 95 scope of the invention.

Having thus described my invention, I claim:

1. A non-refillable receptacle having the combination of a straight wall, an adjacent 100 arched wall concentric with one of the edges of said wall, a wall hinged at said edge adapted to swing toward the interior side of said straight wall while its edge swings along said arched wall and bears thereagainst, means to prevent return swinging of said hinged wall, and a valve in said straight wall to permit the contents to issue therefrom upon swinging of said hinged wall. 105

2. A non-refillable receptacle having the combination of a straight wall, an adjacent arched wall concentric with one of the edges of said wall, a wall hinged at said edge 5 adapted to swing toward the interior side of said straight wall while its edge swings along said arched wall and bears thereagainst, and means to prevent return swinging of said hinged wall.
- 10 3. A non-refillable receptacle having the combination of a straight wall, an adjacent arched wall, a hinged wall adapted to swing toward said straight wall and along said arched wall, means to prevent return swinging 15 of said hinged wall, and a valve in said straight wall to permit the contents to issue

therefrom upon swinging of said hinged wall.

4. A non-refillable receptacle having the combination of a wall, an arched wall, a 20 hinged wall adapted to swing along said arched wall, means to prevent return swinging of said hinged wall, and means to permit the contents to issue from the receptacle upon swinging of said hinged wall. 25

Signed at the city of New York, in the county of New York, and State of New York, this 15th day of March, A. D. 1916.

MIGUEL DE MARIA ARRIOJA.
